Primary Examiner—Ted Shooman*Assistant Examiner*—Richelle Shelton*Attorney, Agent, or Firm*—Brinks Hofer Gilson & Lione**[57]****CLAIM**

The ornamental design for a basketball backboard cover, as shown and described.

DESCRIPTION

FIG. 1 is a perspective view of a basketball backboard cover showing the new design, the basketball hoop shown in broken lines is for illustrative purposes only and forms no part of the claimed design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a side elevational view thereof for ease of illustration due to the flexible structure, the draw string varies slightly in position throughout the figures.
